NON-VIBRATIONAL DENTAL TOOL
Ferenc H. Fodor, 7463 Melrose Ave.,
Los Angeles 46, Calif.
Filed Nov. 7, 1960, Ser. No. 67,811
14 Claims. (Cl. 32—27)

This invention relates to a dental tool and more particularly, to a very smooth running, high-speed drilling tool having exceptionally low vibration characteristics, whereby the tool is particularly adapted for dental and surgical use.

With the advent of the use of high-speed drilling tools in the dentistry profession, the proficiency with which a dentist may drill cavities in teeth has been greatly increased and the pain normally encountered by a patient during such drilling operations has been considerably reduced. Such reduction in pain encountered by the patient is generally due to the higher cutting speeds now employed which allow the completion of a drilling operation before the temperatures of the tooth and cutting tool become high enough to disturb the adjacent nerve endings.

The reduction in cutting temperature by increased cutting speed, however, has been accompanied by an increase in vibration of the cutting tool due to the higher r.p.m. of the rotating parts employed. It has been found that vibration is a major cause of pain experienced by the patient during a drilling operation due to aggravation of the nerve endings near the drilling area. In addition, when very high drilling speeds are used, there is a tendency for the drill to continue turning after the driving mechanism is de-energized due to the large inertia forces built up at such high speeds. A deeper cavity than desired is frequently, though inadvertently, thereby drilled. The difference between a very uncomfortable toothache and a successful drilling operation may depend on whether the drill stops turning in rapid response to the will of the operator. Furthermore, after drill penetration of the tooth enamel, slower drilling speeds are preferable due to the softer inner tooth material, dentin and pulp, and due to the proximity of the drilling tool with the nerve center of the tooth.

It is, therefore, a primary object of this invention to disclose and provide a high-speed dental drilling tool which is very smooth running, and substantially free of nerve aggravating vibration.

It is another object of this invention to disclose and provide an adjustable-speed dental drilling tool which may be rapidly started and stopped at the will of the operator.

A further object of the invention is to disclose and provide a substantially gearless driving mechanism employing permanent magnet couplings and friction drive connections to obtain smooth non-vibrational operation of a drilling tool.

A still further object of this invention is to disclose and provide an easily manipulated, self-contained, non-vibrational drilling tool easily manipulated while drilling teeth in a patient's mouth, which is economical to manufacture, portable to be easily carried and sterilized, and possesses a long useful life.

Generally stated, the invention comprises a hollow separable body portion, preferably composed of three housings or shell members; an elongated power drive shell, a central handpiece shell and a headpiece shell. The elongated power drive shell is provided with motor drive means preferably in the form of an electric motor of the adjustable speed type positioned in the rearward portion of the power drive shell. The motor shaft extends forwardly within the power drive shell. A speed reducing drive assembly may be optionally provided immediately forward of the motor as part of the motor drive means

2

and is engaged by a forward portion of the motor shaft. Such an assembly may be provided to improve motor torque of the commonly used small high speed electrical motors. This speed reducing drive assembly may be omitted when a suitably high speed, high constant torque motor of small size is employed. Immediately forward of the motor drive means there is provided a selectively operable magnetic clutch means which is associated with the motor drive means and when operated, engages a clutch shaft connecting it to the motor drive means. A magnetic brake assembly is also provided in association with the clutch shaft to effect a rapid stopping of the drill when operating even at very high speeds.

The centrally located handpiece shaft is of virtually cylindrical dimensions to be easily manipulated and contains a handpiece shaft which is driven by the clutch shaft by way of a positive mechanical connection between the two.

A magnetic coupling comprised of two permanent magnet members, preferably made of ceramic permanent magnet material, is provided in the forward portion of the handpiece shell coupling the handpiece shaft to a coupling shaft in the headpiece shell. Such connection tends to eliminate any jerky, sporadic movements or vibrations caused by the motor drive means.

The aforementioned coupling shaft, provided in the headpiece shell, transmits the driving power of the motor means from the magnetic coupling to a drilling tool through a driving connection between the two. In addition, a magnetic chuck may be provided in association with the driving connection to magnetically hold and position a drilling tool relative to the headpiece in operable position.

A more detailed description of exemplary embodiments of the non-vibrational dental tool according to the invention will be hereafter presented with references made to the appended sheet of drawings in which:

FIG. 1 is a side elevation of the exterior of a non-vibrational dental tool according to the invention;

FIGS. 2 and 2a are a side sectional view of the dental tool of FIG. 1 sectioned longitudinally along a vertical plane passing generally through the central axis of the tool;

FIG. 3 is a cross sectional view of the dental tool of FIG. 2 along the plane III—III;

FIG. 4 is an alternative embodiment of a portion of the dental tool of FIG. 2a;

FIG. 5 is another alternative embodiment of a portion of the dental tool of FIG. 2a; and

FIG. 6 is a detail view of a portion of the alternative embodiment of FIG. 5 along the plane V—V.

Referring first to FIG. 1, the non-vibrational dental tool, according to the invention, comprises a hollow separable body portion preferably constructed of three shell or housing members which enclose the driving mechanism of the tool. The central housing member, as shown in FIGS. 1, 2 and 2a, is a straight hand piece shell 1 consisting of a virtually cylindrical hollow handpiece adapted to be easily grasped and manipulated. The rear end of the handpiece shell 1, as seen in FIG. 2, is provided with an internal taper to receive the interconnecting holding member 2. Holding member 2 is of a generally frustoconic external configuration having a flange area 3 at the larger rearwardly facing end and has a bore 4 axially aligned therethrough. The internal taper of the rear end of the handpiece shell 1 mates with the external taper of the interconnecting holding member 2 to effect a tight or press fit maintaining the two parts in an interconnected assembled relationship.

A handpiece shaft 5 is axially journaled within the handpiece shell 1 by means of the ball bearings 6 and 7,

as shown in FIGS. 2 and 2a. The forward end of the handpiece shaft 5 is adapted to receive a magnetic coupling member 8, which is preferably of two diameter cylindrical construction having a generally T shaped cross section and presents a forwardly facing, generally circular surface, or face. The rearward end of the handpiece shaft 5 is tapered toward that end to be readily inserted and received within the bore of a clutch shaft 9. Handpiece shaft 5 and clutch shaft 9 may be made in one piece but the embodiment here shown is preferable to allow ease of assembly and disassembly of the tool. The forward bearing 7 abuts against the magnetic coupling member 8 and the rearward bearing 6 abuts against the interconnecting holding member 2. A tubular separator 10 is provided to separate and position the bearings 6 and 7 relative to the handpiece shaft 5 positioning the non-rotating outer race portion of the bearing 6 in abutting engagement with the member 2 and the rotating inner race of bearing 7 against the rotatable coupling 8. A sleeve 10' may also be employed to hold and position the outer races of ball bearings 6 and 7 within the handpiece shell 1 by a frictional fit between the sleeve 10' and shell 1, and between sleeve 10' and ball bearings 6 and 7.

The rear housing is an elongated power drive shell 11 which may be removably mounted upon the rearward end of the handpiece shell 1, in axial alignment therewith, by means of the interconnecting holding member 2. Power drive shell 11 is preferably a virtually cylindrical shell closed at its rear end except for an oil hole 12 and open at its forward end. The forward end of shell 11 is tapered to provide an internal thread to allow the shell 11 to be removably screwed onto external threads on the flange 3 of the interconnecting member 2, effecting the connection indicated generally at 13 in FIG. 2.

High-speed electrical motor drive means are provided adjacent the rearward end of the separable body of the tool, as shown in FIG. 2, wherein a motor 14 is positioned within the power drive shell 11 toward the rearward end of shell 11. Since the dental tool is most effective when operated at high speeds and it is also desirable to be able to adjust the speed of the motor, a suitable adjustable speed, normally polyphase, A.C. motor should be employed. I have found that a two phase, 4 pole, 400 cycle, 26 volt, A.C. motor is particularly suitable for use in my "Non-Vibrational Dental Tool." A motor shaft 15 is journaled on ball bearing 16 at the rear wall of the power drive shell 11 and on ball bearing 17 at a ported divider wall 18. Ported divider wall 18 may be positioned within shell 11 by providing raised beads 18' on the inner surface of the power drive shell 11 and is ported to allow the motor shaft 15 to pass therethrough.

A speed reducing drive assembly, indicated generally at 20 in FIG. 2, may also be optionally provided within the power drive shell 11, forward of the motor 11 and separated therefrom by the divider wall 18, to act as part of the motor driving means when greater motor torque is required than the particular motor employed will provide without reduction gearing. Motor shaft 15 extends forwardly through the divider wall 18 where a forward portion 15' cooperates with and drives the optional speed reducing drive assembly. As shown in the embodiment of FIG. 2, the assembly consists of a cylindrical cup-like housing member 21, having a cover plate 22; an internal gear 23; and a pinion 24. The cup-like housing member 21 is provided with a rearwardly directed open end to receive the plate 22 and a forwardly directed ported end to receive the drive shaft 27. Cover plate 22 is adapted to close the rearwardly directed open end of the cup-like housing member 21 and is ported to receive therethrough the forwardly extending motor shaft 15. Pinion 24 is rotatably journaled upon the cover plate 22 in the upper half of the housing member 21 by means of the shaft 25. Shaft 25 is fixed within the bore of the pinion 24 and journaled within a ball bearing 26, which in turn is fixedly mounted within the cover plate 22. Pinion 24

is thereby positioned within the cup housing member 21 of the speed reducing drive assembly to be engaged and driven by the forward gear portion 15' of the motor shaft 15. The pinion 24, in turn, drives the internal gear 23, effecting a reduction of the motor speed and an increase in torque, promoting smooth running characteristics of the tool. Internal gear 23 is mounted on the drive shaft 27, which is journaled in the forward wall of the planetary drive housing 21 by means of the ball bearing 28, and is thereby adapted to cooperate with the selectively operable magnetic means indicated generally at 30. When a constant torque high speed electric motor having superior torque producing characteristics is employed, the motor shaft 15 and drive shaft 27 may be provided as one integral shaft. Such embodiment is preferred.

Selectively operable magnetic means are provided to selectively drive and stop the drilling tool. Such means are comprised of selectively energized magnetic clutch means and non-rotating magnetic brake means.

The magnetic clutch means, also contained within the power drive shell 11, is comprised of an electro-magnet 31 and a spring finger assembly 32. The magnetic clutch is a form of friction clutch in which the friction surfaces are brought into contact by electro-magnet 31 instead of by some mechanical means. An advantage of this clutch is that it may be operated at higher rotative speeds than mechanical clutches and stands up well under heavy duty high speed driving. Electro-magnet 31 is preferably of generally ring construction adapted to present a forwardly facing generally flat annular surface and is rotatably mounted upon the magnetic drive shaft 27. Electro-magnet 31, therefore rotates along with the drive shaft 27 as the latter is impelled by the motor driving means. Spring finger assembly 32 is positioned in register with the forwardly facing annular surface of the electromagnet 31 by being fixedly mounted on the clutch shaft 9, which is in substantial axial alignment with the drive shaft 27 and motor shaft 15. The assembly 32 is comprised of individual spring fingers 33 and a ring 34 about the periphery, as shown in FIG. 3.

Upon energization of the electromagnet 31, the ring 34 and spring fingers 33 of the assembly 32, being preferably made of a ferrous material, are attracted to and are magnetically bound to the electromagnet 31, effecting a connection between the drive shaft 27 and the clutch shaft 9. The rotation of the handpiece shaft 5 may, therefore, be rapidly started, the motor 14 being already in operation, by merely completing a circuit to the electromagnet 31 and thereby causing the clutch means to be rapidly engaged.

A magnetic brake assembly is also provided within the power drive shell 11 just forward of the magnetic clutch means. A brake spring finger assembly 36, having spring fingers bounded by a ring member similar to assembly 32, is mounted on the clutch shaft 9 forward of the spring finger assembly 32 and presents a forwardly facing surface to contact an electromagnet 37. Electromagnet 37 is preferably of generally ring construction, presenting a rearwardly facing generally flat annular surface, and is fixedly, non-rotatably mounted on the rear wall of the interconnecting holding member 2. The ring member and spring fingers of brake spring finger assembly 36 are positioned in register with such rearwardly facing surface of electromagnet 37. The energizing of the electromagnet 37 by means of a suitable electric circuit causes the brake spring fingers and ring member of assembly 36, being preferably made of a ferrous material, to be attracted to and bound against the rearwardly facing annular surface of the electromagnet 36. To stop the handpiece shaft 5, the magnetic clutch means, indicated generally at 30, is de-energized and the magnetic brake assembly is simultaneously activated. Such operation stops the shaft rotation very rapidly by the braking action of the brake spring finger assembly 36 binding against the brake electromagnet 37.

The clutch elements, clutch spring finger assembly 32 and the brake spring finger assembly 36, may be provided as a single element which would alternately engage the electromagnets 31 and 37. However, the embodiment shown in FIG. 2 is preferable since the air gap between assembly 32 and electromagnet 31 and between assembly 36 and electromagnet 37 may be readily adjusted by providing adjustable spring means extending between the fingers of assembly 32 and assembly 33. By varying the tension in such spring means, the air gaps may be equally enlarged or narrowed as desired by pulling the fingers of the two assemblies nearer together or allowing them to relax to a normal position in which the ring members of the assemblies are in close proximity to the electromagnets. Such spring means may be provided by attaching tension springs between various aligned fingers of the two assemblies, which, as shown in FIG. 2, have a common hub 35 mounted on the clutch shaft 9. The tension spring ends may be attached to the spring fingers by screws or bolts which may be screwed in or out of the fingers to vary the tension in the springs.

It may be seen, therefore, that by the use of such magnetic clutch means and a magnetic brake means, together with a suitable power source, wiring and switches of conventional types, the handpiece shaft 5 is adapted to be very rapidly accelerated to the r.p.m. of the drive shaft 27, the motor driving means being already in operation turning the drive shaft 27 at a high r.p.m., and may also be very rapidly decelerated to a stopped position, at the will of the operator. The forces created in such rapid starting and stopping of the shaft 5 are distributed over the circular faces of the electromagnets 31 and 37 such that an even distribution of load is provided. Such distribution of the starting and stopping torque loads restrains vibrations and jerking motions to a minimum.

The forward housing member, as shown in FIG. 2a, is an angle headpiece shell 40 which is removably mounted on the forward end of the handpiece shell 1. As seen in FIG. 2a, the headpiece shell 40 is preferably of a right angle generally cylindrical construction with a coupling shaft 41 journaled therein in substantial axial alignment with the handpiece shaft 5. A drill 42 is axially journaled therein at generally right angles to the axis of the coupling shaft 41 and the handpiece shaft 5. Headpiece shell 40 is preferably removably attached to a cylindrical coupling shell 43 by means of a threaded, screw type connection at 44. The coupling shell 43 is, in turn, removably connected to the forward end of the handpiece shell 1 by the threaded connection at 45.

Coupling shaft 41 is journaled on the ball bearings 46 and 47 and is provided with a magnetic coupling member 48 on its rearward end. Coupling member 48 is preferably of two diameter cylindrical construction, having a generally T shaped cross section and presents a rearwardly facing circular surface or face adapted to contact the forwardly facing magnetic coupling member 8 on the forward end of the handpiece shaft 5.

The coupling members 8 and 48 are permanent magnets which adhere to each other to effect a magnetic coupling. Such permanent magnets may be made of Alnico or of ceramic permanent magnet material. I have found that ceramic permanent magnets, pressed and formed from ceramic material, are preferable since they provide very good, workable magnets that are less expensive than corresponding metal magnets. The magnetic coupling formed by the coupling members 8 and 48 provides a very smooth running coupling which transmits the driving power of the handpiece shaft 5 to the coupling shaft 41.

The forward end of the coupling shaft 41 is provided with a permanent magnet 49 made of Alnico or, preferably, a ceramic permanent magnetic material. The inner rotating races of the bearings 46 and 47 abut against the permanent magnets 48 and 49, respectively, and are separated and positioned by a tubular separator 50.

Headpiece shell 40 is also provided with a driving con-

nnection between the coupling shaft 41, and, therefore, handpiece shaft 5, and the drill 42. Such connection as shown in FIG. 2a is comprised of the permanent magnet 49, acting as a burr drive member, axially mounted on the forward end of the coupling shaft 41 and a friction disk 51. The burr 49 is a generally round, rod-like member with an enlarged head portion at the forward end.

Friction disk 51 is preferably made of a ferrous material, responsive to the magnetic attraction exerted thereon by the permanent magnet burr 49, and is provided with a rectangular bore to receive a portion of the drill 42. Friction disk 51 is axially journaled within the headpiece shell 40 with its axis at a generally right angle to that of the burr 49 by means of the ball bearings 52 and 53 so that it is positioned to be rotated by the burr 49. The surface 54 of the burr 49 and the surface 55 of the disk 51 are adapted to mate with each other in a magnetic friction drive connection, the disk 51 being positioned below the burr 49 in the lower portion of the headpiece shell 40.

A permanent magnet chuck 56 made of Alnico or, preferably, of ceramic permanent magnet material, may also be provided within the headpiece shell 40 in association with the friction disk 51. The magnetic chuck 56 is preferably of a generally disk-like configuration suitable to be magnetically attracted to and thereby engage the underside of the friction disk 51 effecting a magnetic coupling.

Chuck 56, being a permanent magnet, is adapted to magnetically hold the drill 42, preferably made of a ferrous material, with sufficient force to maintain it in position during a drilling operation yet allow relatively easy disengagement of the drill 42 manually. Drill 42 may be provided with a circular plate or disk-like portion 58 to provide surface area to effect such magnetic engagement of the drill 42 to the underside of the chuck 56. A ring holder 57 may be also employed to provide a guide member to guide and laterally restrain the rotating disk-like portion 58 of drill 42.

The shaft of drill 42 is preferably provided with a rectangular cross section such that when positioned within the rectangular bore of friction disk 51, a mechanical connection is obtained between the drill 42 and disk 51. The magnetic chuck 56 is also provided with a bore of sufficient diameter to allow the shaft of drill 42 to pass up into the cylindrical pillar portion of the disk member 51 which is journaled on the ball bearing 52. The drill 42 is rotated along with the chuck 56 by the disk 51 as the burr drive member 49 drives the disk 51.

The provision of this magnetic driving connection and the use of magnetic couplings, according to the invention, produce a very smooth running vibration free dental tool which is particularly adapted for use at very high rotation speeds. Furthermore, the positioning of the optional planetary drive assembly with the pinion 24 in the upper portion of the housing 21 and the driving contact area between the burr 49 and disk member 51 in the lower portion of the headpiece shell 40 causes the torque producing loads in the two areas to be 180° out of phase and thereby offsetting of each other. A smooth constant drive is thereby promoted avoiding sporadic movements on starting and stopping of the tool as well as undue vibrations or erratic motion of the tool due to its high speeds of rotation when employed in high speed drilling operations.

An alternative construction of the invention is shown in FIG. 4. In this alternative embodiment, the headpiece shell 60 is straight and of generally cylindrical construction having a coupling shaft 61 rotatably journaled therein on the ball bearings 62 and 63, which are separated by a tubular separator 66. A permanent magnet coupling member 64 is provided on the rearward end of the shaft 61 to couple with the coupling member 8 of the dental tool of FIG. 2a. A permanent magnet chuck 65 may be provided on the forward end of the shaft 61 to hold and position the drill 42. The rectangular shaft of

drill 42 may be inserted into the bore of shaft 61 which is of suitable rectangular configuration to effect a driving connection therebetween.

The drill 42 is, therefore, rotated by the shaft 61 in response to the operation of the dental tool by the operator through the magnetic coupling effected by coupling members 8 and 64.

Another alternative embodiment of a dental tool according to the invention, is shown in FIG. 5. Here the coupling shell 70 is provided with a bend at its rearward end to provide an angled relationship between the headpiece shell 80 and the handpiece shell 1. The coupling shaft is provided in two parts, forward shaft 71 journalled on the ball bearing 72 and a rear shaft 73 journalled on the ball bearing 74, the two shafts being axially aligned with each other but describing an obtuse angle therebetween. An angled magnetic drive is provided between the shaft 71 and the shaft 73 in the form of a permanent magnet drive member 75, provided on the forward end of rear shaft 73 and presenting a forwardly facing generally convex surface, and a permanent magnet driven member 76 provided on the rearward end of forward shaft 71 and having a rearwardly facing, generally concave surface, the convex and concave surfaces of the respective magnets meeting in an angled magnetic friction drive connection.

The headpiece shell 80 may also alternatively be provided with an adjustable swinging head of a generally ball and socket type. As shown in FIG. 5, the headpiece shell 80 may be provided with a socket member 81, shown therein in cross section. An inner ball head member 82 is positioned therein and is held into the socket 81 and restrained into arcuate rotation in one plane only by a dovetail or gib 83 which slides within a way or spline 84 in the socket 81. A slot 85 is provided within the inner ball head member 82, the gib 83 terminating at said slot, to allow the inner head member 82 to swing within the socket 81 without binding upon the shaft 71.

The driving connection between the coupling shaft 71 and the drill 42 in the embodiment of FIG. 5 comprises the permanent magnet 86, having a forward ball head acting as a burr drive member. Friction disk 87 is mounted in the radial bearing 53 and is provided with a convex surfaced portion 88 which is engaged and frictionally driven by the permanent magnet 86. The frictional drive between disk 87 and burr 86 is enhanced by the magnetic attraction exerted by permanent magnet burr 86 upon the preferably metallic disk 87. The magnetic chuck 56 holds drill 42 in place against disk 87, the drill 42 being guided by the ring holder 57. A mechanical drive connection may be effected between drill 42 and disk 87 by providing a rectangular bore within disk 87 into which a rectangular portion of the shaft or shank of drill 42 may engagingly protrude.

The exemplary embodiments of the non-vibrational dental tool described herein in detail are not intended to be exhaustive of all possible embodiments of the invention and it should be understood that other modifications, alterations and embodiments may be made within the scope of my invention as defined by the following claims:

I claim:

1. A hand-held, smooth running, easily manipulated, non-vibrational dental tool comprising: a virtually cylindrical hollow handpiece shell having a handpiece shaft axially journalled therein, said handpiece shaft having a forwardly facing permanent magnet coupling member carried on a forward end of said handpiece shaft; an elongated power-drive shell removably connected to a rear end of said handpiece shell and in axial alignment therewith, said power-drive shell containing an electric motor, a speed reducing drive operably connected thereto and a clutch shaft in axial alignment therewith; magnetic clutch means adapted to selectively connect the speed reducing drive to the clutch shaft; a magnetic brake assembly associated with said clutch shaft, said clutch shaft being in axial alignment with and being adapted to driv-

ingly engage the handpiece shaft in all positions of the magnetic clutch and brake assembly; a headpiece shell removably attached to the forward end of said handpiece shell, said headpiece shell including a coupling shaft journalled therein, said coupling shaft carrying a permanent magnet coupling member having a rearwardly directed face adapted to contact the forwardly facing permanent magnetic coupling member of said handpiece shaft; and a driving connection between said coupling shaft and a drilling tool mounted within said headpiece shell.

2. A hand-held, smooth running, easily manipulated, non-vibrational dental tool comprising: a virtually cylindrical hollow handpiece shell having a handpiece shaft axially journalled therein, said handpiece shaft having a forwardly facing permanent magnet coupling member carried on a forward end of said handpiece shaft; an elongated power-drive shell removably connected to a rear end of said handpiece shell and in axial alignment therewith, said power-drive shell containing an electric motor, a speed reducing drive operably connected thereto and a clutch shaft in axial alignment therewith said electric motor being located in the rearward portion of said power-drive shell and provided with a motor shaft which extends forwardly within said power-drive shell, said speed reducing drive being located within said power-drive shell forward of said motor and comprising: a cup-like housing axially aligned within the power drive shell having a rearwardly directed open end and a forwardly directed ported end; a drive shaft extending into said cup-like housing through said forwardly directed ported end; an internal tooth gear rotatably mounted within said cup-like housing in axial alignment therein and mounted upon said clutch shaft, a cover plate adapted to close said rearwardly directed open end of said cup-like housing, said plate being ported to receive therethrough said forwardly extending motor shaft; and a pinion rotatably mounted on said cover plate within said cup-like housing and adapted to interengage said motor shaft and said internal tooth gear.

3. A non-vibrational dental tool as in claim 2 wherein said driving connection in said headpiece shell comprises: a permanent magnet burr drive member axially mounted on a forward end of said coupling shaft in axial alignment therewith, said burr having an enlarged forward head portion; and a friction disk member axially journalled within in said headpiece shell with its axis at a generally right angle to that of said drive member, the disk being adapted to be rotated about its axis by the rotation of said burr about its own axis by said head portion of said burr contacting said disk in a magnetic friction drive; and wherein said pinion is positioned within said cup-like housing in an upper portion of said housing and power drive shell, and said friction disk member is located within said headpiece shell in a lower portion of said shell beneath said burr driver.

4. A hand-held, smooth running, easily manipulated, non-vibrational dental tool comprising: a virtually cylindrical hollow handpiece shell having a handpiece shaft axially journalled therein, said handpiece shaft having a forwardly facing permanent magnet coupling member carried on a forward end of said handpiece shaft; an elongated power-drive shell removably connected to a rear end of said handpiece shell and in axial alignment therewith, said power-drive shell containing an electric motor, a speed reducing drive operably connected thereto and a clutch shaft in axial alignment therewith, magnetic clutch means adapted to selectively connect the speed reducing drive to the clutch shaft; a magnetic brake assembly associated with said clutch shaft, said magnetic brake assembly including a non-rotating electromagnet fixedly mounted within said power-drive shell presenting a generally flat, rearwardly facing, angular face, and a brake spring finger assembly fixedly mounted on said clutch shaft being provided with a forwardly facing angular surface in substantial register with said rearwardly

facing annular surface of said non-rotating electromagnet, said clutch shaft being in axial alignment with and being adapted to drivingly engage the handpiece shaft in all positions of the magnetic clutch and brake assembly; a headpiece shell removably attached to the forward end of said handpiece shell, said headpiece shell including a coupling shaft journalled therein, said coupling shaft carrying a permanent magnet coupling member having a rearwardly directed face adapted to contact the forwardly facing permanent magnetic coupling member of said handpiece shaft; and a driving connection between said coupling shaft and a drilling tool mounted within said headpiece shell.

5. A hand-held, smooth running, easily manipulated, non-vibrational dental tool comprising: a virtually cylindrical hollow handpiece shell having a handpiece shaft axially journalled therein, said handpiece shaft having a forwardly facing permanent magnet coupling member carried on a forward end of said handpiece shaft; an elongated power-drive shell removably connected to a rear end of said handpiece shell and in axial alignment therewith, said power-drive shell containing an electric motor, a speed reducing drive operably connected thereto and a clutch shaft in axial alignment therewith; magnetic clutch means adapted to selectively connect the speed reducing drive to the clutch shaft; a magnetic brake assembly associated with said clutch shaft, said clutch shaft being in axial alignment with and being adapted to drivingly engage the handpiece shaft in all positions of the magnetic clutch and brake assembly; a headpiece shell removably attached to the forward end of said handpiece shell, said headpiece shell including a coupling shaft journalled therein, said coupling shaft carrying a permanent magnet coupling member having a rearwardly directed face adapted to contact the forwardly facing permanent magnetic coupling member of said handpiece shaft; and a driving connection between said coupling shaft and a drilling tool mounted within said headpiece shell, said driving connection including a permanent magnet driving member provided on a forward end of said coupling shaft and a friction disk axially disaligned with said coupling shaft and associated with said drilling tool to provide common rotation of said disk and said drilling tool, said disk being adapted to be rotatably driven by said permanent magnet driving member.

6. A hand-held, smooth running, easily manipulated, non-vibrational dental tool comprising: a virtually cylindrical hollow handpiece shell having a handpiece shaft axially journalled therein, said handpiece shaft having a forwardly facing permanent magnet coupling member carried on a forward end of said handpiece shaft; an elongated power-drive shell removably connected to a rear end of said handpiece shell and in axial alignment therewith, said power-drive shell containing an electric motor, a drive shaft associated with said motor, and a clutch shaft in axial alignment therewith; magnetic clutch means adapted to selectively connect the motor associated drive shaft with said clutch shaft; a magnetic brake assembly associated with said clutch shaft; said clutch shaft being in axial alignment with and being adapted to drivingly engage the handpiece shaft in all positions of the magnetic clutch and brake assembly; a headpiece shell removably attached to a forward end of said handpiece shell, said headpiece shell including a coupling shaft journalled therein, said coupling shaft carrying a permanent magnet coupling member having a rearwardly directed face adapted to contact the forwardly facing permanent magnet coupling member of said handpiece shaft; and a driving connection between said coupling shaft and a drilling tool mounted within said headpiece shell, said driving connection including a permanent magnet driving member provided on a forward end of said coupling shaft and a friction disk axially disaligned with said coupling shaft and associated with said drilling tool to provide common rotation of said disk and said drilling tool, said disk being

adapted to be rotatably driven by said permanent magnet driving member.

7. A non-vibrational dental tool as in claim 6 wherein in said headpiece shell is provided with a magnetic chuck associated with said disk member to magnetically hold and position said drilling tool relative to said headpiece shell, said magnetic chuck being a disk-like permanent magnet positioned against the underside of said friction disk.

10 8. A hand-held, smooth running, easily manipulated, non-vibrational dental tool comprising: a virtually cylindrical hollow handpiece shell having a handpiece shaft axially journalled therein, said handpiece shaft having a forwardly facing permanent magnet coupling member carried on a forward end of said handpiece shaft; an elongated power-drive shell removably connected to a rear end of said handpiece shell and in axial alignment therewith, said power-drive shell containing an electric motor, a speed reducing drive operably connected thereto and a clutch shaft in axial alignment therewith; a magnetic clutch means adapted to selectively connect the speed reducing drive to the clutch shaft; a magnetic brake assembly associated with said clutch shaft, said clutch shaft being in axial alignment with and being adapted to drivingly engage the handpiece shaft in all positions of the magnetic clutch and brake assembly; a headpiece shell removably attached to the forward end of said handpiece shell, said headpiece shell including a coupling shaft journalled therein, said coupling shaft carrying a permanent magnet coupling member having a rearwardly directed face adapted to contact the forwardly facing permanent magnetic coupling member of said handpiece shaft; a driving connection between said coupling shaft and a drilling tool mounted within said headpiece shell, said driving connection including a permanent magnet driving member provided on a forward end of said coupling shaft and a friction disk axially disaligned with said coupling shaft and associated with said drilling tool to provide common rotation of said disk and said drilling tool, said disk being adapted to be rotatably driven by said permanent magnet driving member; and a magnetic chuck provided within said headpiece shell and associated with said driving connection to magnetically hold and position said drill within said headpiece shell, said magnetic chuck being a disk-like permanent magnet.

5 9. A hand-held, smooth running, easily manipulated, non-vibrational dental tool comprising: a virtually cylindrical hollow handpiece shell having a handpiece shaft axially journalled therein, said handpiece shaft having a forwardly facing permanent magnet coupling member carried on a forward end of said handpiece shaft; an elongated power-drive shell removably connected to a rear end of said handpiece shell and in axial alignment therewith, said power-drive shell containing an electric motor, a drive shaft associated with said motor, and a clutch shaft in axial alignment therewith; magnetic clutch means adapted to selectively connect the motor associated drive shaft with said clutch shaft; a magnetic brake assembly associated with said clutch shaft; said clutch shaft being in axial alignment with and being adapted to drivingly engage the handpiece shaft in all positions of the magnetic clutch and brake assembly; a headpiece shell removably attached to a forward end of said handpiece shell, said headpiece shell including a coupling shaft journalled therein, said coupling shaft carrying a permanent magnet coupling member having a rearwardly directed face adapted to contact the forwardly facing permanent magnet coupling member of said handpiece shaft, and an angled coupling shell interconnecting said handpiece shell and said headpiece shell; and a driving connection between said coupling shaft and a drilling tool mounted within said headpiece shell; said coupling shaft being comprised of two parts, a forward shaft and a rear shaft, said shafts being interconnected by an angled magnetic friction drive comprising: a permanent magnet drive member provided

on a forward end of said rear shaft and presenting a forwardly facing, generally convex surface and a permanent magnet driven member provided on a rearward end of said forward shaft having a rearwardly facing, generally concave surface, said convex and said concave surfaces of said permanent magnets meeting in an angled magnetic friction drive connection.

10. A non-vibrational, virtually gearless drilling tool comprising: a hollow, separable body portion provided with a high speed electrical motor drive means contained adjacent one end of such body portion; a magnetic chuck carried by the other end of said body portion, said other end of said body portion extending at an angle to the remainder of the body portion; a shaft journaled between said chuck and motor means, said shaft including two sections thereof with axes at an angle to each other; and permanent magnet coupling members carried by said shaft sections forming a driving connection therebetween, said coupling members including opposed permanent magnets engaging each other in a magnetic friction drive connection wherein one permanent magnet is provided with a generally convex contact surface and the other of said magnets is provided with a generally concave contact surface.

11. In a non-vibrational, virtually gearless drilling tool having a body portion provided with a high speed electrical motor drive means contained adjacent one end of said body portion, a drilling tool chuck carried by the other end of said body portion; a shaft journaled in said body portion and extending between said chuck and motor means; and selectively operable clutch means for engaging and disengaging said motor means with said shaft, the provision of: a permanent magnet driving member on a forward end of said shaft and a friction disk axially disaligned with said shaft and associated with said drilling tool chuck to provide common rotation of said disk and chuck, said disk being adapted to be rotatably driven by said permanent magnet driving member.

12. In a non-vibrational dental tool having a hollow, separable body portion provided with a high speed electrical motor drive means contained adjacent one end of such body portion; a drilling tool carried by the other end of said body portion, a shaft journaled within said body portion and between said drilling tool and motor means; and selectively operable clutch means for engaging and disengaging said motor means and said shaft, the provision of: a permanent magnet driving member on a forward end of said shaft, a friction disk axially disaligned with said coupling shaft adapted to be rotatably driven by said permanent magnet driving member, and a magnetic chuck associated with said disk member and body portion to magnetically hold and position a drilling tool relative to said body portion, said magnetic chuck being a disk like permanent magnet positioned against an underside of said friction disk to provide common rotation of said disk, magnetic chuck and drilling tool.

13. A hand-held, smooth running, easily manipulated, non-vibrational dental tool comprising: a virtually cylindrical hollow handpiece shell having a handpiece shaft axially journaled therein, said handpiece shaft having a forwardly facing permanent magnet coupling member carried on a forward end of said handpiece shaft; an

elongated power-drive shell removably connected to a rear end of said handpiece shell and in axial alignment therewith, said power-drive shell containing an electric motor, a drive shaft associated with said motor, and a clutch shaft in axial alignment therewith; magnetic clutch means adapted to selectively connect the motor associated drive shaft with said clutch shaft; a magnetic brake assembly associated with said clutch shaft; said clutch shaft being in axial alignment with and being adapted to drivingly engage the handpiece shaft in all positions of the magnetic clutch and brake assembly; a headpiece shell removably attached to a forward end of said handpiece shell, said headpiece shell including a coupling shaft journaled therein, said coupling shaft carrying a permanent magnet coupling member having a rearwardly directed face adapted to contact the forwardly facing permanent magnet coupling member of said handpiece shaft; and a driving connection between said coupling shaft and a drilling tool mounted within said headpiece shell.

20. 14. A non-vibrational, virtually gearless drilling tool comprising: a hollow, separable body portion provided with a high speed electrical motor drive means contained adjacent one end of such body portion, a magnetic chuck carried by the other end of said body portion, a shaft journaled between said chuck and motor means, and selectively operable magnetic means for disconnecting said motor means from said shaft and positively stopping rotation of said shaft, said selectively operable magnetic means including: a first electromagnet rotatable by said motor means and having a generally flat, forwardly facing annular surface; a non-rotatable second electromagnet fixedly mounted within said body portion spaced from said first electromagnet and having a generally flat rearwardly facing annular surface; and two spaced spring finger assemblies fixedly mounted on said shaft, a first spring finger assembly of said assemblies having a rearwardly facing annular surface in substantial register with said forwardly facing annular surface of said first electromagnet and being adapted to be magnetically attracted to said first electromagnet upon its energization to effect a magnetic friction engagement between said shaft and said motor means, a second spring finger assembly of said assemblies having a forwardly facing annular surface in substantial register with said rearwardly facing annular surface of said non-rotating second electromagnet and being adapted to be magnetically attracted to said second electromagnet upon its energization to effect a braking action on said shaft.
